DESIGN FOR AN INSPECTION LIGHT

Joseph J. W. Stephens, South Pasadena, and
Kenneth M. Cross, Glendale, Calif.

Application April 13, 1943, Serial No. 109,966

Term of patent 7 years

To all whom it may concern:

Be it known that we, Joseph J. W. Stephens and Kenneth M. Cross, citizens of the United States, residing at South Pasadena, in the county of Los Angeles and State of California, and Glendale, in the county of Los Angeles and State of California, respectively, have invented a new, original and ornamental Design for an Inspection Light, of which the following is a specification, reference being had to the accompanying drawing forming a part thereof.

In the accompanying drawing:

Fig. 1 is a side elevational view of an inspection light showing our design;

Fig. 2 is a front elevational view;

Fig. 3 is a top plan view;

Fig. 4 is an enlarged sectional view taken on line 4—4, Fig. 1, and

Fig. 5 is a bottom plan view.

We claim:

The ornamental design for an inspection light, as shown.
